UNITED STATES PATENT OFFICE

153,031

DESIGN FOR A COMB

Alfred F. Pope, Hudson, Mass.

Application May 2, 1947, Serial No. 138,772

Term of patent 7 years

(Cl. D86—8)

To all whom it may concern:

Be it known that I, Alfred F. Pope, a citizen of the United States, residing at Hudson, in the county of Middlesex and State of Massachusetts, have invented a new, original, and ornamental Design for a Comb, of which the following is a specification, reference being had to the accompanying drawings, forming a part thereof.

I claim:

The ornamental design for a comb, as shown.

ALFRED F. POPE.
